RALPH L. SKINNER, OF DETROIT, MICHIGAN, ASSIGNOR TO SKINNER MOTORS, INC., OF DETROIT, MICHIGAN, A CORPORATION OF DELAWARE

INTERNAL-COMBUSTION ENGINE SEALING-RING HOLDING-MEANS

Application filed April 4, 1931. Serial No. 527,662.

In internal-combustion engines of the style comprising an exterior, ported cylinder, an interior, unported cylinder, inside of and spaced concentrically slightly away from the 5 encasing, outer cylinder, a cylinder-head projecting down into the outer cylinder with a shallow, annular space between the two, a power-piston slidable in said inner cylinder, a split, expandable and contractible, ported 0 sealing-ring bearing endwise on the top of the inner cylinder which terminates below the inlet and exhaust ports of the outer cylinder, means in association with the cylinder-head and sealing-ring to seal or confine the 5 gas pressures in the combustion-chamber of the engine, arcuate or substantially semi-circular, ported valves sliding between the outer cylinder on the one hand, and the inner cylinder, sealing-ring, hold-down ring and cylinder-head on the other hand, with suitable 0 means for reciprocating the valves in proper manner, difficulty has heretofore arisen in providing suitable and efficient means for preventing turning of the sealing-ring, 5 which, if allowed to take place, would result in lack of the needed, proper and continuous registration of its ports with those of the valves and those of the outer cylinder.

It has been suggested to employ a positioning or locating pin mounted in the cylinder-head and projecting into a cavity or recess in the inner surface of the sealing-ring, but such a combination of parts has not been found to be satisfactory, because the pin 5 necessarily partakes of the more or less radical expansions and contractions of the cylinder-head which is subjected to high temperatures because it is in direct contact with the hot explosion gases in the combustion-chamber.

Such a pin may bind on the margin of the ring recess or carbon may progressively form in such cavity with the result, in either case, that a prohibitory or unallowable binding 5 action occurs between the ring and the one or more valves against which it presses outwardly.

The present invention is designed to furnish convenient, suitable and simple means 0 for maintaining such sealing-ring in place

without the occurrence of any objectionable or detrimental results.

In the accompanying drawings, constituting a part of this specification, and to which reference should be had in connection with the following detailed description, a present, desirable or preferred embodiment of the invention has been illustrated, so that those skilled in this art may have a full and complete understanding of the invention, both from structural and functional standpoints.

For simplicity, like reference numerals have been employed to designate the same parts throughout the views of the drawings.

In the drawings:—

Figure 1 is a fragmentary, vertical, central section through the upper portion only of one cylinder of a multi-cylinder internal-combustion engine incorporating the invention;

Figure 2 is a fragmentary, vertical section on line 2—2 of Figure 1;

Figure 3 is a fragmentary, horizontal section on line 3—3 of Figure 1; and

Figure 4 is a perspective view of the ported sealing-ring comprising a part of the engine structure.

Turning to the drawings, it will be perceived that the engine includes the already known, external or outer, water-jacketed cylinder 11 having the customary inlet and exhaust ports 12 and 13, respectively, the companion, unported, inner cylinder 14 supported solely from below, by means not shown, and terminating at its top end below the specified ports of the outer cylinder, the power-piston 15 reciprocating in such inner cylinder and which is connected to the engine crank-shaft by the usual connecting-rod, neither of which have been illustrated, the

longitudinally-split, expandable and contractible, ported sealing-ring 16 having a seat at its lower end on the top edge of the inner cylinder, such sealing-ring having a bridged inlet-port 17 and an unbridged or unobstructed exhaust-port 18, which are in register with the corresponding or companion admission and discharge ports 12 and 13 of the outer cylinder, a continuous or unsplit hold-down ring 19 bearing directly on the top of the

sealing-ring, a plurality or group of inclined, nested, flexible reeds 21 appropriately mounted on the cylinder-head 22 and bearing at their outer edges on the inner surface of the 5 hold-down ring, coiled springs 23 and their whole or divided ring 24 located between the cylinder-head and the hold-down ring, and ported, arcuate or semi-circular inlet and exhaust valves 25 and 26 having admission and 10 discharge ports 27 and 28 and located between, and slidable lengthwise between, the outer cylinder, in which they fit, and, on the inside, the inner cylinder, sealing-ring, hold-down ring and cylinder-head, these valves 15 being reciprocated in proper manner and in correct timed relation to the actuation of the other parts of the engine by means not depicted.

The engine, so far as thus described, does 20 not incorporate the present invention, but the latter will now be considered in detail.

To prevent the sealing-ring from turning around more or less and to insure a constant, proper registration of its two ports 25 with the companion ones of the outer cylinder, a pin or lug 29 is screwed into and projects outwardly from an otherwise unapertured part of the sealing-ring between its inlet and exhaust ports, such pin extending 30 through an elongated space 31 between the adjacent edges of the two valves, each of which is cut away slightly at 32 to unitedly and conjointly provide the gap referred to, 35 into a groove 33 cut in the inner surface of the outer cylinder wall lengthwise the latter from its top end downwardly.

Inasmuch as groove 33 is provided in a water-cooled wall, the pin is not subjected to such substantial changes in temperature as it 40 might otherwise be and the construction avoids mounting of the pin on the cylinder-head, which, because it forms directly a wall of the engine combustion-chamber, is subjected to much higher temperatures.

45 This locating-pin is preferably out of contact with the sliding valves, thus avoiding the possibility of any binding action between the two, the positioning or holding function being performed by the co-operation of the 50 pin with the wall or walls of the cylinder groove.

It will be noted that the sealing-ring ports are not in the center of the ring, that is, they are not midway between its top and bottom, 55 which necessitates that care be exercised in not getting the ring in place upside down.

By limiting the length of groove 33 in proper manner and by locating the pin on the ring in a suitable way, the presence of the 60 pin will prevent the operator from inserting the ring in the engine in a wrong manner, that is, upside down.

If properly introduced into the engine, the ring will seat on the inner cylinder and the pin will occupy the lower portion of the

engine-cylinder groove, but if it be attempted to insert the ring upside down, the pin will bear on the bottom end wall of the groove before the ring reaches the inner cylinder, and it will be impossible to mount the cylinder-head properly since it cannot then be fully introduced into the cylinder, the ring being in the way.

Thus the pin and its co-operating or companion groove perform this added beneficial function of precluding incorrect positioning of the sealing-ring in the structure.

Although I have shown the recessing of the approximate edges of the two valves to supply the space for the reception of the locating or holding pin, this construction being preferable because it minimizes the reduction in pressure sealing surface of the valves, it does not preclude the recessing of one valve only to allow the positioning pin to extend through into the cylinder groove.

Obviously, by this novel and improved construction, I have avoided the mounting of the ring-locating pin on the cylinder-head with its accruing disadvantages.

Although I have shown and described only one particular embodiment of this invention, those acquainted with this art will understand that it is susceptible of a variety of embodiments, the scope of the invention being defined by the appended claims.

I claim:

1. The combination of an outer ported cylinder, a head for said cylinder, an inner cylinder inside of and spaced away from said outer cylinder, a piston slidable in said inner cylinder, means to seal the fluid pressures in said outer cylinder above said piston including an expansible and contractible ported sealing-ring bearing endwise on the upper end of said inner cylinder with its port-means in substantial register with that of said outer cylinder, arcuate reciprocatory valve-means sliding between said outer cylinder on the one side and said inner cylinder and sealing-ring on the other side, and a positioning-lug and recess connection between said sealing-ring and outer cylinder to prevent the sealing-ring from turning.

2. The combination of an outer cylinder having inlet and discharge ports, a head for said cylinder, an inner cylinder inside of and spaced away from said outer cylinder, a piston slidable in said inner cylinder, means to seal the fluid pressures in said outer cylinder above said piston including an expansible and contractible sealing-ring bearing endwise on the upper end of said inner cylinder and having inlet and discharge ports in substantial register with those of said outer cylinder, arcuate reciprocatory inlet and discharge valves sliding between said outer cylinder on the one side and said inner cylinder and sealing-ring on the other side and adapted to open and close said ports, and a position-

ing-lug and recess connection between said sealing-ring and outer cylinder to prevent the sealing-ring from turning.

3. The combination of an outer ported cylinder, a head for said cylinder, an inner cylinder inside of and spaced away from said outer cylinder, a piston slidable in said inner cylinder, means to seal the fluid pressures in said outer cylinder above said piston including an expandible and contractible ported sealing-ring bearing endwise on the upper end of said inner cylinder with its port-means in substantial register with that of said outer cylinder, arcuate reciprocatory valve-means sliding between said outer cylinder on the one side and said inner cylinder and sealing-ring on the other side, and a positioning-lug on and projecting from the outer face of said sealing-ring into a recess in the inner surface of said outer cylinder.

4. The combination of an outer cylinder having inlet and discharge ports, a head for said cylinder, an inner cylinder inside of and spaced away from said outer cylinder, a piston slidable in said inner cylinder, means to seal the fluid pressures in said outer cylinder above said piston including an expandible and contractible sealing-ring bearing endwise on the upper end of said inner cylinder and having inlet and discharge ports in substantial register with those of said outer cylinder, arcuate reciprocatory inlet and discharge valves sliding between said outer cylinder on the one side and said inner cylinder and sealing-ring on the other side and adapted to open and close said ports, and a positioning-lug on and projecting from the outer face of said sealing-ring into a recess in the inner surface of said outer cylinder.

5. The combination of an outer ported cylinder, a head for said cylinder, an inner cylinder inside of and spaced away from said outer cylinder, a piston slidable in said inner cylinder, means to seal the fluid pressures in said outer cylinder above said piston including an expandible and contractible ported sealing-ring bearing endwise on the upper end of said inner cylinder with its port-means in substantial register with that of said outer cylinder, arcuate reciprocatory valve-means sliding between said outer cylinder on the one side and said inner cylinder and sealing-ring on the other side, and a positioning-lug on and projecting from the outer face of said sealing-ring into a recess in the inner surface of said outer cylinder, said valve-means being cut away to allow said lug to project therethrough into its co-operating recess.

6. The combination of an outer cylinder having inlet and discharge ports, a head for said cylinder, an inner cylinder inside of and spaced away from said outer cylinder, a piston slidable in said inner cylinder, means

to seal the fluid pressures in said outer cylinder above said piston including an expandible and contractible sealing-ring bearing endwise on the upper end of said inner cylinder and having inlet and discharge ports in substantial register with those of said outer cylinder, arcuate reciprocatory inlet and discharge valves sliding between said outer cylinder on the one side and said inner cylinder and sealing-ring on the other side and adapted to open and close said ports, and a positioning-lug on and projecting from the outer face of said sealing-ring into a recess in the inner surface of said outer cylinder, one at least of said valves being cut away to allow said lug to project therethrough into said cylinder recess.

7. The combination of an outer cylinder having inlet and discharge ports, a head for said cylinder, an inner cylinder inside of and spaced away from said outer cylinder, a piston slidable in said inner cylinder, means to seal the fluid pressures in said outer cylinder above said piston including an expandible and contractible sealing-ring bearing endwise on the upper end of said inner cylinder and having inlet and discharge ports in substantial register with those of said outer cylinder, arcuate reciprocatory inlet and discharge valves sliding between said outer cylinder on the one side and said inner cylinder and sealing-ring on the other side and opening and closing said ports, and a positioning-lug on and projecting from the outer face of said sealing-ring into a recess in the inner surface of said outer cylinder, the adjacent edges of said valves being cut away for the accommodation of said lug.

8. The combination of an outer cylinder having inlet and discharge ports, a head for said cylinder, an inner cylinder inside of and spaced away from said outer cylinder, a piston slidable in said inner cylinder, means to seal the fluid pressures in said outer cylinder above said piston including an expandible and contractible sealing-ring bearing endwise on the upper end of said inner cylinder and having inlet and discharge ports in substantial register with those of said outer cylinder, arcuate reciprocatory valve-means sliding between said outer cylinder on the one side and said inner cylinder and sealing-ring on the other side and opening and closing said ports, the ports of said sealing-ring being located nearer one end thereof than the opposite end, said cylinder having a longitudinal groove in its inner surface extending downwardly from its upper end, and a lug on and projecting from the outer face of said sealing-ring into said cylinder groove, the length of said groove and the location of said lug on said sealing-ring permitting the sealing-ring to seat on the upper end of said inner cylinder only when the sealing-ring ports

are in substantial register with the corresponding outer cylinder ports.

9. The combination of an outer cylinder having inlet and discharge ports, a head for said cylinder, an inner cylinder inside of, spaced inwardly away from, and terminating below the ports of, said outer cylinder, a piston slidable in said inner cylinder, means to seal the fluid pressures in said outer cylinder above said piston including an expansible and contractible sealing-ring bearing endwise on the upper end of said inner cylinder and having inlet and discharge ports in substantial register with those of said outer cylinder, the ports of said sealing-ring being nearer one end thereof than the opposite end, substantially semi-circular reciprocatory inlet and discharge valves sliding between said outer cylinder on the one side and said inner cylinder and sealing-ring on the other side and opening and closing said ports, said cylinder having a longitudinal groove in its inner surface extending downwardly from its upper end, and a positioning-lug on and projecting from the outer face of said sealing-ring into said cylinder groove, the length of said groove and the location of said lug on said sealing-ring permitting the sealing-ring to seat on the upper end of said inner cylinder only when the sealing-ring ports are in substantial register with the corresponding outer cylinder ports, the adjacent edges of said two valves being cut away for the accommodation of said lug.

35 In witness whereof I have hereunto set my hand.

RALPH L. SKINNER.
